UNITED STATES PATENT OFFICE.

HERMAN BELDOCH, OF NEW YORK, N. Y., ASSIGNOR OF ONE-HALF TO BENJAMIN LESSER, OF BROOKLYN, NEW YORK.

RAZOR-BLADE HOLDER.

1,163,061.

Specification of Letters Patent.

Patented Dec. 7, 1915.

Application filed May 13, 1915. Serial No. 27,759.

To all whom it may concern:

Be it known that I, HERMAN BELDOCH, a citizen of the United States, and a resident of New York, borough of Brooklyn, in the county of Kings and State of New York, have made and invented certain new and useful Improvements in Razor-Blade Holders, of which the following is a specification.

This invention relates to a razor blade holder, and has for its object to provide an article which will most rigidly and securely grip razor blades, allowing them to be conveniently stropped and sharpened, the device being so formed that it may be used for holding and stropping a variety of different types of razor blades.

A further object is to provide an article of this class which is of simple and neat construction, and one that can be economically manufactured.

A further object of the invention is to so form the device that the blades may be easily and quickly inserted in place in the holder and so clamped, the procedure being such that the danger of being cut by the edge of the razor blade is reduced to a minimum and practically eliminated.

A further object is to provide a holder, for razor blades, employing but few parts and so constructed that the device will withstand considerable and hard usage, and will not be materially affected by water, to which it is necessarily exposed from time to time during its ordinary use.

Other objects and advantages will appear as the description proceeds, wherein it is to be understood that changes in the precise embodiment of the invention can be made within the scope of what is claimed, without departing from the spirit thereof.

The preferred embodiment of my invention is disclosed in the accompanying drawings, wherein:

Figure 1 is a view in perspective of the razor blade holder embodying the characteristic features of my invention, the holder being illustrated in its opened position prior to the securing of a razor blade therein. Fig. 2 is a view in plan of a Gillette razor blade, the same being one type of blade which my holder is particularly adapted to

engage or clamp. Fig. 3 is a view in plan of the holder with a Gillette razor blade in position therein, illustrating the convenient manner in which both edges of the blade 55 may be stropped, and the manner in which the blade is secured and locked in position. Fig. 4 is a view in longitudinal section, taken on the line 4—4 of Fig. 3. Fig. 5 is an enlarged view of the upper portion of the 60 holder and illustrating the manner in which one end of the Gillette blade is held in place. Fig. 6 is a view in cross-section taken on the line 6—6 of Fig. 5. Fig. 7 is a detail view in perspective of the locking ring by means 65 of which the separable portions of the holder are forcibly moved together for the clamping 70 of a razor blade. Fig. 8 is a fragmental view in plan of the device, showing the manner in which a razor blade of the Durham-Duplex type is held. Fig. 9 is a view in cross-section taken on the line 9—9 of Fig. 8. Fig. 10 is a detail view in plan of this type of razor blade. Fig. 11 is a similar 75 view, showing the manner in which a somewhat different type of blade is held; the blade in this instance being provided with but a single cutting edge, and with the opposite edge thickened and reinforced. Fig. 12 is a view in cross-section taken on the 80 line 12—12 of Fig. 11. Fig. 13 is a detail view in plan of this latter-mentioned type of razor blade.

Referring specifically to the several views, the holder is formed with the two clamping 85 members 15—15, preferably formed of spring metal, such as German silver, and struck from a single length, which is bent upon itself at its central portion, which latter forms the lower or handle end 16 of 90 the device. The clamping members are of thin but wide material, and of such length as to be conveniently held in the hand, so that a blade which is secured between the free ends of the clamping member may be 95 conveniently stropped.

The free ends 17—18 of the clamping members are each provided with the longitudinal extending recesses 19—19 which allow the holder to engage, and properly 100 clamp, razor blades of that type which are provided with one edge thickened and rein-

forced, the thickened and reinforced edge of the blade being adapted to seat within the recesses 19, as more fully hereinafter described. One of the clamping members is 5 provided, adjacent its end, with the inwardly struck lug 20, which is adapted to seat within an opening 21 provided in the other of the clamping members and in alignment or registration therewith. The lug is 10 thus adapted to engage and seat within an opening 22 in the razor blade, such as, for example, one of that type manufactured by the Gillette Razor Company, and illustrated in Fig. 2. The locking ring 24 is slidably 15 mounted upon the clamping members 15—15 and is prevented from traveling or moving beyond the connected ends thereof by a knob or projection 25. The knob or projection may be soldered to one of the clamping 20 members, but is preferably formed as disclosed in Fig. 4, by placing the device between suitable dies and so forming the projection or lug 25 therein, the lug in this case being accompanied by a corresponding 25 depression.

The locking ring is preferably formed from a single piece of material and is of such size that the clamping members are forcibly driven together as the ring is moved 30 therealong. In order to prevent the ring from passing beyond the free ends of the clamping members, they are widened somewhat at their upper extremities, as at 26. The locking ring is provided at its upper 35 and side edges with the notches 27, which are adapted to receive therein the lower edge of a razor blade, and hold the same against shifting, this action being clearly illustrated in Fig. 5. The upper or end opening 22 of 40 the blade is placed over the lug 20, and the clamping member moved into forcible contact with the lower and curved edge of the blade 28, it being noted that the lower edge of the blade is formed as an arc of a circle 45 materially greater than an arc described about the lug 20 as the center. The holding action for blades of the above-mentioned type thus depends on a positive engagement with the upper opening of the blade, a frictional engagement with the lower edge 50 thereof by the locking ring, and the general frictional engagement of the blade by the clamping members caused by their forcible contact therewith on account of the position 55 of the locking ring, all of which result in the most rigid securing of the blade.

The clamping members are so formed that as the locking ring is moved to its position at the joined ends of the clamping members, their free ends will spring apart, as 60 illustrated in Fig. 1, allowing the blade to immediately drop therefrom, thus minimizing the amount of handling of the blade.

The separated condition of the clamping members also facilitates the insertion and 65 securement of a blade therein.

In using the device with a blade of the type manufactured by the Durham-Duplex Company, and illustrated in Fig. 10, the longitudinal slot 29 is placed over the holding 70 lug or member 20 and the locking ring moved toward the same, this type of blade being of such length and thickness that the locking ring 24 does not ordinarily contact with the lower edge of the blade but moves 75 the clamping members into such forced contact therewith as to hold the blade rigidly in position, allowing it to be conveniently stropped and without danger of it shifting during such procedure. 80

The recesses 19 which are provided in the clamping members are adapted to receive the reinforced edges 30 of that type of blade, which is illustrated in Figs. 11 to 13, this being similar to the blades as manufactured 85 by the Gem Safety Razor Company, and others. As the locking ring 24 is moved to the position as illustrated in Fig. 11, the clamping members are brought into forcible contact with the razor blade and rigidly lock 90 it in position within the holder and allow it to be conveniently stropped and sharpened. The device as thus constructed is adapted 95 for use with a variety of different types of safety razor blades, is of neat and attractive appearance, and may be economically manufactured, involving but few operations and forms a convenient, as well as effective, means for holding razor blades for stropping. 100

What I claim is:—

A razor blade holder comprising connected clamping members, substantially rectangular in cross-section, with the free extremities of said clamping members adapted to spring 105 apart, one of said clamping members provided adjacent its free extremity with an outstanding projection, the other of said clamping members provided with an opening 110 receiving therein registering with, and adapted to receive, said projection, a locking ring, substantially rectangular in cross-section, slidably mounted upon said clamping members, means located at the opposite ends of said clamping members preventing the disengagement of said locking ring therefrom, 115 the sides of said locking ring corresponding to the edges of said clamping members provided with V-shape notches therein alining with the confronting faces of said clamping members and held in such alignment by the cross-sectional contour of said locking ring and clamping members, said clamping members adapted to receive a razor blade therebetween, said locking ring adapted to force 120 the projection of one of said clamping mem- 125

bers through an opening in said razor blade and into engagement with the side walls of the registering opening of the other of said clamping members, to move the ends of said clamping members forcibly together, for the frictional engagement of said blade throughout its length, and to wedgedly engage the

lower edge of said razor blade within said V-shape notches of the locking ring.

Signed at New York, borough of Manhattan, in the county of New York and State of New York, this 12th day of May, A. D. 1915.

HERMAN BELDOCH.
